J. L. WEINMANN

SEAL

Filed May 1, 1922

Inventor:

John L. Weinmann

By Louis McCandless, Atty.

UNITED STATES PATENT OFFICE.

JOHN L. WEINMANN, OF ST. LOUIS, MISSOURI, ASSIGNOR TO ST. LOUIS PERFECT LOCK-
SEAL COMPANY, OF ST. LOUIS, MISSOURI, A CORPORATION OF MISSOURI.

SEAL.

Application filed May 1, 1922. Serial No. 557,593.

To all whom it may concern:

Be it known that I, JOHN L. WEINMANN, a citizen of the United States of America, a resident of the city of St. Louis, in the 5 State of Missouri, have invented certain new and useful Improvements in Seals, of which the following is a full, clear, and exact description, reference being had to the accompanying drawings, forming a part 10 of this specification.

This invention relates to improvements in seals, and particularly to devices of this character which may be applied without the use of tools to freight cars to lock the 15 doors thereof and which, when applied, cannot be removed without breaking or destroying the seal.

A still further object is to provide a seal of simple and inexpensive construction 20 which is formed entirely of a single strip of metal and is provided with reinforcing means whereby the strip of metal of which said seal is formed may withstand the strains to which it is subjected.

With the foregoing and other objects in view, the invention comprises the novel construction, combination and arrangement of parts hereinafter more specifically described and illustrated in the accompanying drawings 25 wherein is shown the preferred embodiment of the invention. However, it is to be understood that the invention comprehends changes, variations and modifications which come within the scope of the claims 30 hereunto appended.

Fig. I is a plan view of my seal strip as it appears when stamped out for use and before the body of the seal is folded.

Fig. II is an edge view of the seal strip 40 shown in Fig. I.

Fig. III is a perspective view of the seal as it appears when in use.

Fig. IV is a section on line IV—IV of Fig. I.

Fig. V is a section on line V—V of Fig. I.

Fig. VI is an enlarged fragmentary section through the body of the seal showing said seal in a locked position.

In the drawings, A designates my seal strip as it will appear before being folded in a manner to be hereinafter explained to provide for the formation of holding members, by which the tongue of the shackle is held. The strip A comprises a body portion 50 B and a shackle-forming tongue C. A portion of the body portion B is struck up to form a raised keeper 1, and extended through said body at one end of the keeper 1 is a transverse opening 2.

In forming the seal from the strip A, I bend the body portion of the strip on a transverse line *a* contiguous to the opening 2, and fold what I term the catch section 3 rearwardly against the keeper section 4. 65 I then fold the body B on a line *b* to form a rear guard section 5, which lies against the back of and protects the intermediate catch section 3. The several sections 3, 4 and 5 are secured to each other in any suitable manner after the folds have been made, and as a most economical means of fastening said sections, I punch holes 6 through the several sections and upset the spurs produced by the punching operation to form 70 rivet members 7 (Fig. III). The holes just referred to are preferably formed so that they extend through the keeper section 4 at opposite sides of the keeper 1, as seen in Fig. III, and therefrom through the sections 2 and 3.

In forming the seal strip I strike a tang 8, which is so disposed that it lies in the catch section 3 and projects forwardly from said section when the body of the strip is 85 folded, as explained, and lies within the keeper 1 of the keeper section 4, as seen in Fig. VI. To reinforce the tang 8 so that it may be better able to withstand strain to which it may be subjected, I provide 90 said tang with a reinforcing rib 9, which extends longitudinally of said tang. Also in forming the seal strip I produce in the tongue of the strip apertures 10, through which the tang 8 is adapted to extend when 95 the tongue of the strip is bowed into shackle form and inserted through the keeper 1 of the keeper section 4. Adjacent to each

of the apertures 10 is a flexible extension 11 which is produced by forming a pair of parallel slits in the metal of the tongue of the strip for a slight distance beyond said aperture, said slits being continuations of and in alinement with the side margins of the apertures, the free end of each of said flexible extensions forming the end margin of one of said apertures.

10 To prevent the tongue of the strip from being weakened because of the absence of the metal which is removed to produce the apertures 10, I arrange reinforcing members 12 which extend around said apertures on three sides thereof, said reinforcing portions being in the form of U-shaped ribs pressed outwardly from the body of the tongue.

When the body of the seal has been folded 20 to produce the sections 3, 4 and 5, the tongue of the seal extends rearwardly from the keeper section 4, and in putting the seal in service it is only necessary to loop the tongue C so that its end may be inserted through 25 the opening 2 and through the keeper 1, where it will be interposed between the section 3 and the section 4 of the body portion B (Fig. IV). In so doing I provide a shackle formed from the tongue C, said 30 tongue extending through the keeper 1 and between the front of the keeper and the portion of the catch section 3 immediately back of the front of the keeper and which is occupied by the tang 8. In inserting the 35 tongue of the seal through the keeper 1, the tongue traverses the tang 8, and upon any attempt to withdraw the tongue from said keeper, the tang 8 enters into one of the apertures 9 and prevents the withdrawal of 40 said tongue. By providing the flexible extensions 11 an additional grip is obtained between the tang 8 and tongue C, as said flexible extensions 11 may be drawn into 45 closer contact with and conform to the shape of the tang than if said tang contacted with a rigid portion of said tongue. The tongue is therefore so gripped as to be securely held against backward movement, with the 50 result of effectually preventing the opening of the seal.

I preferably provide a number of apertures 10 in the tongue C in order that a larger or smaller shackle may be provided, as may be desired or required.

55 I claim:

1. A seal comprising a strip having a body formed and folded to provide a keeper section and a catch section, lying one in front of the other, a tongue extending from 60 said body, said tongue being provided with apertures, said keeper section being provided with a keeper and said catch section being provided with a tang extending into said keeper, said tang being adapted to enter an 65 aperture in said tongue when the latter is

inserted into said keeper, and reinforcing means on said tongue adjacent to said apertures.

2. A seal comprising a strip having a body formed and folded to provide a keeper section and a catch section, lying one in front of the other, a tongue extending from 70 said body, said tongue being provided with apertures, said keeper section being provided with a keeper and said catch section being provided with a tang extending into 75 said keeper, said tang being adapted to enter an aperture in said tongue when the latter is inserted into said keeper, and U-shaped reinforcing means on said tongue adjacent to 80 said apertures.

3. A seal comprising a strip having a body formed and folded to provide a keeper section and a catch section, lying one in front of the other, a tongue extending from 85 said body, said tongue being provided with apertures, said keeper section being provided with a keeper and said catch section being provided with a tang extending into 90 said keeper, said tang being adapted to enter an aperture in said tongue when the latter is inserted into said keeper, and reinforcing means comprising ribs on said tongue adjacent to 95 said apertures.

4. A seal comprising a strip having a 100 body formed and folded to provide a keeper section and a catch section, lying one in front of the other, a tongue extending from said body, said tongue being provided with apertures, said keeper section being provided with a keeper and said catch section being provided with a tang extending into 105 said keeper, said tang being adapted to enter an aperture in said tongue when the latter is inserted into said keeper, and reinforcing means comprising U-shaped ribs on said tongue adjacent to 110 said apertures.

5. A seal comprising a strip having a body formed and folded to provide a keeper section and a catch section, lying one in front of the other, a tongue extending from 115 said body, said tongue being provided with apertures, said keeper section being provided with a keeper and said catch section being provided with a tang extending into said keeper, said tang having a reinforcing rib extending longitudinally thereof and being adapted to enter an aperture in said tongue when the latter is inserted into said keeper, and reinforcing means comprising 120 U-shaped ribs on said tongue adjacent to said apertures.

6. A seal comprising a strip having a body formed and folded to provide a keeper section and a catch section, lying one in front of the other, a tongue extending from 125 said body, said tongue being provided with apertures, said keeper section being provided with a keeper and said catch section being provided with a tang extending into 130 said tongue when the latter is

said keeper, said tang being adapted to enter an aperture in said tongue when the latter is inserted into said keeper and is provided with a reinforcing rib extending longitudinally thereof, independently flexible portions on said tongue adjacent to said apertures adapted to be engaged by said

tang, and reinforcing means on said tongue comprising U-shaped ribs adjacent to said apertures. 10

In testimony that I claim the foregoing I hereunto affix my signature.

JOHN L. WEINMANN.
